UNITED STATES PATENT OFFICE.

JAMES DE WITT HILL, OF SCOTTDALE, PENNSYLVANIA.

AIRCRAFT-PROPELLER.

1,401,537.

Specification of Letters Patent. Patented Dec. 27, 1921.

Application filed May 27, 1919. Serial No. 300,094.

To all whom it may concern:

Be it known that I, JAMES DE WITT HILL, a citizen of the United States, and resident of the city of Scottdale, county of Wyoming, and State of Pennsylvania, have invented a new and useful Improvement in Aircraft-Propellers, of which the following is a specification.

In air craft propellers now in common use, the portions of the blades near the propeller hub are placed at pitch angles unfavorable to the production of thrust, and the blades themselves have fixed pitch angles.

One object of my invention is to increase the efficiency of the propeller by bifurcating the inner or hub ends of the propeller blades and providing these bifurcated portions with a reverse camber and a negative angle of incidence so that the resultant pressure on them becomes an aid to the revolution of the propeller instead of a resistance thereto as in the types now in common use.

Another object of my invention is to increase the efficiency of the propeller by providing propeller blades capable of being rotated to a limited extent on their longitudinal axes, to vary their pitch angle, which axes are inclined outwardly and forwardly with respect to a plane normal to the axis of rotation of the propeller, said blades being provided with trailing means forming an integral part of the blades for automatically varying the pitch angle of the blades to suit different speeds of the air craft, thus permitting the propeller to work under the most favorable conditions and also obtaining the greatest possible flexibility of power application.

Practical embodiments of my invention are represented in the accompanying drawings in which,

Figure 1 represents one form of my improved air craft propeller partly in front elevation and partly in section.

Fig. 2 represents the same in top plan.

Fig. 3 represents a section taken in the plane of the line III—III of Fig. 2.

Figs. 4 to 12 inclusive represent cross sections taken in the planes of the lines IV to XII inclusive of Fig. 2.

Fig. 13 represents another form of my improved propeller partly in front elevation and partly in section.

Fig. 14 represents the same in top plan.

Fig. 15 represents a detail cross section taken in the plane of the line XV—XV of Fig. 13.

Fig. 16 represents a detail view of the synchronizing gearing which connects the two propeller blade shafts.

Figs. 17, 18, 19 and 20 represent diagrammatic views illustrating certain features of the invention.

The propeller shaft is denoted by 1. The propeller hub is fixed to rotate with the shaft 1 and is herein shown as comprising two transverse sections 2 and 3 secured together by means of bolts 4.

Instead of the usual thick blade section near the hub, the blade 5 is bifurcated at its inner or hub end, the bifurcated portions 6 and 7 having a reverse camber and negative angle of incidence. These bifurcated portions are connected adjacent to the hub by a bridge 8 from which a shaft 9 extends into the hub where it is suitably mounted to rotate in antifriction bearings 10, 11. In the form shown in Figs. 1 and 2, these blade shafts 9 are provided with spiral gears 12, which mesh with a spiral gear 13 loosely mounted on the propeller shaft 1 so that the propeller blades are caused to rotate synchronously on their longitudinal axes, to various pitch angles.

The rotary movement of these blades to vary their pitch angles, is limited, as for instance, by providing the gear 13 with lugs 14 located in elongated recesses 15 in the hub. The end walls of these recesses serve as stops to keep the pitch angle of the blades within predetermined limits.

The trailing blade member 16 is integrally connected to the blade 5 by one or more rigid arms 17.

In the form shown in Figs. 13, 14 and 15, the propeller blades are not connected to move synchronously but each of the blade shafts 9 is provided with a lug 18 located in a recess 19, the end walls of which recess serve as stops to limit the rotary movement of the blade between certain predetermined pitch angles.

Light springs 20 are located upon opposite sides of the lug 18 in recesses 21 for normally holding the blade at an intermediate pitch angle, said springs acting as buffers to prevent liability of breaking or distorting the blade when subjected to the strain of starting and stopping.

Dotted line $x-x$ Fig. 2 designates the axis on which the blade revolves and dotted line $y-y$ designates the axis on which the blade rotates to a limited extent. The axis $y-y$ does not necessarily pass through the

axis $x-x$. The axis $y-y$ is shown as inclined outwardly and forwardly with respect to a plane normal to the axis of rotation of the propeller to give the blade an angular setting as shown by the angle $y-o-j$ (Fig. 2).

The blade is arranged to have as nearly as possible, its center of gravity and center of pressure lie in the line $y-y$.

10 In Fig. 3, the pitch angle is denoted by P and the angle of incidence by I . It is clear that the blade at this point will meet the air on its own flight path and if it were turned on that path to the position of bottom side up and the angle I made a negative angle, the lift and drift forces would have the same value, but different directions. In the same manner the pressures acting on the bifurcated portions of the blade are reversed and their resultants are found to lie fairly close to the plane of blade revolution, but they are acting as an assistance to the revolution of the blade. Thus, all of the thrust is produced by the efficient thrust producing portions of the blade, and by this indirect method, the whole area of the blade is made to work at efficient and economical angles.

If we take the given pitch angle of any standard propeller at the blade tip and examine the sections from there toward the hub, we find that the angles gradually increase and approach a limit that would be 90° at the propeller axis. Until these angles attain a value of 45° or a value somewhat greater than 45° , they may be called favorable angles for producing thrust. From this point the blade sections would have angles that would be called unfavorable, and as the pitch of the propeller is increased (and this design applies particularly to propellers of comparatively high pitch) this point of division between the two classifications moves outward toward the tip.

45 In Fig. 17 A, B and C are blade sections: A at the tip, B at the position having a pitch angle of 45° , and C a section of the hub portion. The pitch ratio of this particular layout is 2 to 1.

50 For convenience, the resultant pressures $R-1$, $R-2$ and $R-3$ are assumed to be equal. $T-1$, $T-2$, $T-3$ are thrust components. In passing from A to C the ratios

$$55 \quad \frac{T-1}{R-1}, \frac{T-2}{R-2}, \frac{T-3}{R-3}$$

show a considerable decrease, while the ratios

$$60 \quad \frac{S-1}{T-1}, \frac{S-2}{T-2}, \frac{S-3}{T-3}$$

show a corresponding increase, $S-1$, $S-2$ and $S-3$ being secondary components of the 65 resultant pressures $R-1$, $R-2$, $R-3$, and

since they lie in the plane of rotation they must constitute a resistance to rotation. Therefore, since $T-3$ is of so little value, and $S-3$ is a waste of effort, it would seem that possibly the resultant $R-3$, or the power that produces it, might be used to better advantage.

In Fig. 18 O X is the axis of a propeller, and C is a section of the hub portion of the blade as viewed from the tip. N O is tangent to the spiral flight path of the section and shows the instantaneous direction of the relative wind. The pitch angle is 73° , corresponding to that of C in Fig. 4 and the angle of incidence, (or angle of attack) is 2° . The resultant pressure $R-3$ is assumed perpendicular to the chord. $S-3$ and $T-3$ are its components, $T-3$ being the thrust. Fig. 19 shows a similar lay-out, except that here the camber of C is reversed and the angle of incidence is negative, causing the line of the resultant pressure to move through 4° about O.

Referring to Figs. 18 and 20 C is a section of the usual propeller and in Fig. 19 C is a corresponding section of the propeller described in my application. In both Figs. 18 and 19 C travels on O N at the same speed, so the same power is required in either case, and since the angles of incidence are equal, the resultants $R-3$ and R' are equal, $R-3$ is the result of direct propeller action, while R' (and its components F and G) is the result of a secondary application of power. This power is applied to the blade and the outer portions of the blade, whose efficiency may be assumed at 85% produce thrust, a part of which is used to drive C forward. This means that F and G represent $85/100$ of the power necessary to produce them, therefore in summing up the gains and losses in power units resulting from this change in design, their power equivalents should be used, G then becomes

$Gx \frac{100}{85}$ and F becomes $Fx \frac{100}{85}$ in the graphic representation used.

$T-3$ represents a useful quantity of thrust, and when C is changed to its position in Fig. 19, $T-3$ is lost, so on the line L marked, "Losses," lay off the length $T-3$. $S-3$ is a resistance to rotation and since its removal amounts to a gain, lay off $S-3$ on the line M. In Fig. 19 G is a resistance to forward travel, so it must be called a loss. Lay off its power equivalent $Gx \frac{100}{85}$ on

L. F is an assistance to rotation, and the vector showing the useful fraction of its power equivalent has a length $Fx \frac{100}{85} - F$. This quantity represents a gain, so lay it off on M. Subtract the losses from the gain

$$125 \quad Fx \left(Fx \frac{100}{85} - F \right).$$

This quantity represents a gain, so lay it off on M. Subtract the losses from the gain

as indicated by the dotted line J—K, then K Y represents a definite number of power units now available for, and automatically applied to, the thrust producing outer portion of the blade.

An examination of these pressure reactions on each succeeding section of the blade from the hub toward the tip shows a gradual decrease in the quantity X Y. Beyond the point on the blade at which X Y equals zero it is not profitable to reverse the camber of the sections. The result of this action is purely a gain in propeller efficiency and in no way affects the amount of power applied at the propeller shaft. The object of the design is to secure a coöperation of the effective pressures on the blade for the production of greater thrust.

With reference to the advantage of providing means for automatically varying the pitch angle, the following explanation is given:

It will be seen that centrifugal force tends to throw the freely movable blade with its trailing member into the plane of propeller rotation. This tendency is reduced to a minimum by inclining the longitudinal axis of the propeller blade outwardly and forwardly with respect to a plane normal to the axis of rotation of the propeller sufficient to bring the plane of oscillation to a position of least departure from coincidence with the path of rotation of the center of gravity or concentrated weight of the trailing member. The concentrated weight of the trailing member travels approximately on the surface of an imaginary cylinder whose axis corresponds to the axis of the propeller shaft.

The centrifugal force which tends to throw the freely movable blade with its trailing member into the plane of propeller rotation will tend to cause the blade to rotate on its axis in one direction, and on account of the angular setting of the blade will also tend to cause a departure of the center of gravity or concentrated weight of the trailing member from its centrifugal locus in such a direction that there is a tendency to swing the trailing member in a direction opposite to that of the blade. If then the magnitudes of these two acting forces are equal they may be said to balance each other and thus allow the blade and trailing member to lie properly on the flight path.

We may assume that the blade is balanced on its $y-y$ axis. We will then take a point W and assume that the weight of the entire trailing blade member is concentrated at that point. When the blade at the given pitch angle is revolved about the axis $\alpha-\alpha$, the point W will describe a circle W—R, (Fig. 1) and when given form and motion a straight line through this point W parallel

to the axis $\alpha-\alpha$ generates a cylindrical surface.

When the blade is rotated on the $y-y$ axis, the point W will describe a circle W—R' (Fig. 3).

In order to neutralize the influences of centrifugal force on W it is necessary that the circle or an arc of the circle W—R' shall coincide with the cylindrical surface W—R within the limits X'—X² (Fig. 3).

For all practical purposes this is accomplished by the articulation of the $y-y$ axis as described and shown in Figs. 1 and 2. The points X' and X² in Fig. 3 indicate the limits of variation in pitch angle of the blade.

With the effect of the centrifugal forces neutralized, the trailing blade member 16 is free to trail along behind the blade and lie at all times on the flight path of the blade. Since the blade and its trailing member bear a fixed relationship to each other so that when the trailing member lies on the flight path the blade is held on its given angle of incidence, the conditions necessary for efficient blade action are fulfilled.

The trailing blade member may be of such form and size with respect to the blade area as may be found advisable. Likewise its location with respect to distance from propeller shaft and its distance from the blade may be those found most desirable.

I have shown one form in which the propeller blades are synchronized and another form in which they are not synchronized, but may be permitted to act independently.

The reverse camber feature of the blade is especially applicable to propellers mounted so that the central portion of the thrust area of the propeller is not obstructed by large bodies such as engine housings, radiators, etc.

From the above description it will be seen that by the provision of reversed camber sections near the inner ends of the blades, all portions of the blades may be made to work at more effective angles, thereby materially increasing the efficiency of the propeller. Furthermore, this may be done without weakening the propeller.

By providing a variable pitch for the propeller blade, a maximum efficiency may be obtained regardless of forward speed and also the full power of the motor or any portion thereof may be used at any time regardless of forward speed, thus giving a great advantage particularly in starting and climbing.

It is evident that various changes may be resorted to in the form, construction and arrangement of the several parts without departing from the spirit and scope of my invention, hence I do not wish to be limited to the particular construction herein shown and described, but

What I claim is:

1. A propeller blade having a reverse camber and a negative angle of incidence at its inner end.
5. 2. A propeller blade having a bifurcated inner end, the bifurcated portions having a reverse camber and a negative angle of incidence.
10. 3. In a propeller, a hub, and blades having a reverse camber and a negative angle of incidence adjacent to the hub.
15. 4. In a propeller, a hub, and blades having bifurcated portions adjacent the hub, said bifurcated portions having a reverse camber and a negative angle of incidence.
20. 5. A propeller blade freely rotatable on its own longitudinal axis which is inclined outwardly and forwardly with respect to a plane normal to the axis of rotation of the propeller, said blade having an excess weight on the trailing side of its longitudinal axis.
25. 6. A propeller blade freely rotatable on its own longitudinal axis which is inclined outwardly and forwardly with respect to a plane normal to the axis of rotation of the propeller, said blade having an excess weight on the trailing side of its longitudinal axis and yielding means to normally hold the blade at an intermediate pitch angle.
30. 7. A propeller blade freely rotatable on its own longitudinal axis which is inclined outwardly and forwardly with respect to a plane normal to the axis of rotation of the propeller, said blade having an excess weight on the trailing side of its longitudinal axis and means for limiting the pitch varying movement of the blade.
35. 8. A propeller blade freely rotatable on its own longitudinal axis which is inclined outwardly and forwardly with respect to a plane normal to the axis of rotation of the propeller, said blade having an excess weight on the trailing side of its longitudinal axis,
40. means for limiting the pitch varying movement of the blade and yielding means to normally hold the blade at an intermediate pitch angle.
45. 9. A propeller blade freely rotatable on its own longitudinal axis which is inclined outwardly and forwardly with respect to a plane normal to the axis of rotation of the propeller, and a trailing member forming an excess weight on the trailing side of the longitudinal axis of the propeller blade.
50. 10. A propeller blade freely rotatable on its own longitudinal axis which is inclined outwardly and forwardly with respect to a plane normal to the axis of rotation of the propeller, and a separated trailing member whose center of gravity is located at a point on the trailing side of the longitudinal axis of the propeller blade.
55. 11. A propeller blade freely rotatable on its own longitudinal axis which is inclined outwardly and forwardly with respect to a plane normal to the axis of rotation of the propeller, and a separated trailing member whose center of gravity is located at a point on the trailing side of the longitudinal axis of the propeller blade between the blade and trailing member.
60. 12. A propeller blade freely rotatable on its own longitudinal axis which is inclined outwardly and forwardly with respect to a plane normal to the axis of rotation of the propeller, the center of gravity and center of pressure of said blade lying substantially in said longitudinal axis, and a trailing member whose center of gravity is located on the trailing side of the longitudinal axis of the propeller blade.

In testimony, that I claim the foregoing as my invention, I have signed my name this twenty-third day of May, 1919.

JAMES DE WITT HILL.
